UNITED STATES PATENT OFFICE.

OTTO A. MOSES, OF NEW YORK, N. Y.

VOLTAIC-ARC LAMP.

SPECIFICATION forming part of Letters Patent No. 276,703, dated May 1, 1883.

*Application filed September 13, 1882. (No model.)

To all whom it may concern:

Be it known that I, OTTO A. MOSES, of New York city, in the county and State of New York, have invented a certain new and useful Improvement in Voltaic-Arc Lamps, of which the following is a specification.

The object I have in view is to produce a simple and efficient automatic and continuously-acting regulator for arc-lamps, more especially adapted for a multiple-arc arrangement, but also capable of being used with the lamps in series or multiple series, which regulator will act positively upon the movable carbon in lifting such carbon to establish the arc, and in forcing such movable carbon upon the stationary carbon when the arc is broken, the mechanical connection with the rod or tube carrying the movable carbon not being dependent upon the feeble action of magnetic clamps, which are liable to slip in lifting the upper carbon, the action of the lifting core or armature being quick and forcible. The downward feed of the upper carbon, also, is not dependent wholly upon the weight of the carbon and its holding rod or tube, but when the arc is broken or increased to a definite extent beyond the normal resistance the armature or core drops, and its movement is transmitted positively to the upper carbon, which is forced downwardly thereby. The connection between the core or armature and the tube or rod carrying the upper carbon is of such a nature that it is a positive connection when the movement is a quick one; but the carbon-carrying tube or rod is capable of a retarded downward movement, effected by its own weight, independent of the movement of the core or armature; and it is a further object to provide an effective magnetic clamping device for regulating this retarded feeding movement.

A still further object is to produce simple and efficient means for maintaining uninterruptedly the electrical connection of the upper carbon with the circuit-wire through the moving parts of the regulating mechanism, and preventing bad contact, due to oxidation caused by sparks at points of moving contact.

The features of invention are fully herein-after explained, and are pointed out by the claims.

In the accompanying drawings, forming a

part hereof, Figure 1 is a vertical section of a regulating mechanism embodying my invention; Fig. 2, a cross-section of the carbon-carrying tube, showing the top of the clamping-arms; and Fig. 3, a section of a modified construction.

A represents the coils of a solenoid or hollow electro-magnet, one end of which is connected with circuit-wire 1, while the other end is fastened to the shell a, upon which the coils A are wound, such shell a being connected with the supporting and guiding heads b c.

B is the core or armature of the solenoid or magnet working within and extended below the shell a. This core or armature is also hollow, and has passing through it the tube C, carrying the upper or movable carbon, D, of the lamp, such tube being guided by suitable rings within the hollow core or armature, and being filled with a liquid, D', preferably a viscous liquid, such as glycerine. From the core or armature B rises the tube E, passing through the head b and extending above the same and inclosing the carbon-carrying tube C. A stationary protecting tube may rise from head b and inclose the tube E, if desired, as will be explained hereinafter. Brushes or springs d, carried by head b, press constantly upon the tube E, maintaining good electrical contact with the same. A rod, F, is secured to the upper end of tube E, and extends centrally down within the carbon-carrying tube, through the liquid D' of the same, to near the lower end of the tube when such carbon-carrying tube is at its highest point of movement within the hollow core or armature. At its lower end the rod F carries a piston or plunger, G, which, however, does not fill the tube completely, but permits a definite small flow of the liquid around it. This piston or plunger is provided with spring-wires e, which are secured to such plunger, and spring outwardly, so as to bear constantly against the inner side of the tube C. These spring-wires within the carbon-holding tube maintain uninterruptedly the connection of the upper carbon with the circuit-wire, and the liquid in which these spring-wires are submerged lubricates the surfaces, so that the parts work smoothly, and prevents sparks at the points of contact. The wires e are preferably of copper, although they may be made of

95
100

a magnetic metal, and be plated with copper or not, as found desirable. The piston or plunger may also be either of magnetic or non-magnetic metal. In slots in opposite sides of the core or armature B are pivoted vertical metallic arms H, having clamping-plates f at their upper ends, which bear against the sides of the carbon-carrying tube C. These arms H extend below the core or armature B, and have outwardly-projecting wings g, which carry on their ends armatures I, of iron or other magnetic metal. The core or armature B has wings h, which attract the armatures I when the core is magnetized. The wings h are preferably provided with adjustable pole-pieces, which may be large screws i, turning through such wings. The wings h are connected with the head e by means of spiral springs K, which are adjustably held at one end by means of set-screws k. These springs support the core or armature and the parts connected therewith, and limit as well as cushion the movement of said core or armature.

The operation of the regulator is as follows: Before the circuit to the lamp is completed the parts are in the position shown in the drawings. Upon completion of circuit the core or armature B is magnetized and drawn up into the coils A with a quick and powerful action against the stress of the springs K. The tube E, rod F, and plunger G are raised with the core or armature, and so is the carbon-carrying tube C, which in this quick movement is practically connected positively with the plunger through the liquid D'. This lifting of the carbon D establishes the arc. The magnetism of the core or armature B attracts the armatures I at the adjustable pole-pieces i and forces the clamping-plates f against the tube C'; but these clamps would not alone be sufficient to hold the tube C in the quick upward movement of the core or armature. As the carbous are consumed and the resistance of the arc increases, the magnetism of B is lessened to some extent, and the clamping-plates have their pressure upon the tube C diminished by the weight of the armatures I. The tube C then drops, its movement being retarded by the resistance to the flow of the liquid around the plunger until the magnetism of B is increased and the carbon-holding tube is again clamped. In this way a continuous feed of the upper carbon is maintained. If the arc is broken or increased to a definite extent beyond the normal resistance, the core or armature will drop, carrying the tube E and rod F and plunger G with it. The tube C will also be forced down positively by this movement through the liquid, the weight of the core or armature and attached parts and the force of the springs K being added to the weight of the carbon-carrying tube.

Instead of supporting the core and other parts by means of the springs K, the modified arrangement illustrated in Fig. 3 may be em-

ployed. Here an outer stationary tube M, 70 incloses the tube E. Such tube M is supported on the top plate, b, of the solenoid or magnet. A spiral spring, L, attached to the top of tube M, is attached also to tube E, so that the latter is supported by said spring. This arrangement is equivalent to that before described. A suitable device, m, is employed to adjust the tension of the spring L.

What I claim is—

1. In regulators for arc-lamps, the combination, with a solenoid or electro-magnet and its hollow movable core or armature, of a carbon-carrying tube passing through such hollow core or armature and containing fluid, and 80 a plunger located within such tube and connected with the said core or armature, substantially as set forth.

2. In regulators for arc-lamps, the combination, with a solenoid or electro-magnet and its 85 hollow movable core or armature, of a carbon-carrying tube containing liquid and passing through such hollow core or armature, a tube rising from the core or armature and inclosing the carbon-carrying tube, and a plunger 90 secured to said outer tube and working in the fluid of the carbon-carrying tube, substantially as set forth.

3. In regulators for arc-lamps, the combination, with a solenoid or electro-magnet and its 95 movable core or armature, of a carbon-carrying tube or rod connected with the core or armature through a fluid column, and having a retarded movement independent of such core or armature, and a magnetically-operated clamp 100 for regulating this retarded independent movement, substantially as set forth.

4. In regulators for arc-lamps, the combination, with a solenoid or electro-magnet and its movable core or armature, of a carbon-carrying tube connected with such core or armature through a fluid column, and a clamp or clamps pivoted to such movable core or armature, and having an armature or armatures attracted by said movable core or armature, 105 such clamp or clamps acting upon the carbon-carrying tube, substantially as set forth.

5. In regulators for arc-lamps, the combination, with a solenoid or electro-magnet and its 110 movable core or armature, of the clamps pivoted to such core or armature and themselves carrying armatures, and the adjustable pole-pieces carried by the main core or armature, substantially as set forth.

6. In regulators for arc-lamps, the combination, with a carbon-carrying tube, of an interior contact piece or pieces for maintaining the circuit-connection with the movable carbon 115 uninterrupted, substantially as set forth.

This specification signed and witnessed this 120 5th day of September, 1882.

OTTO A. MOSES.
